APPARATUS FOR APPLYING AND REMOVING VALVE FITTINGS IN GAS CYLINDERS

William H. Loveman, Shaker Heights, Ohio

Application March 8, 1944, Serial No. 525,552

3 Claims. (Cl. 29—240)

This invention relates to a machine for applying and removing valve fittings in gas cylinders and similar containers. Gas such as oxygen, hydrogen, acetylene and the like are stored in heavy metal containers called "cylinders" under considerable pressure, sometimes as much as 3000-4000 pounds per square inch. These containers usually have in one end thereof a fitting which includes a valve and dispensing outlet through which the gas is delivered and discharged. This fitting or valve is threadedly secured into the metal cylinder. Considerable force is required to secure these valves in place, and if manually done requires a wrench from three to five feet in length and the full strength of two men. I have designed a power-operated machine for this purpose which eliminates the human factor and applies the same force to each fitting.

One of the objects of this invention is to provide a power-driven tool for securing and removing valves or fittings in gas cylinders which includes an automatic clutch which is disconnected when the force applied exceeds a predetermined amount.

Another object of the invention is to provide a tool of the character described which is adjustable as to height as well as angularly so that no precise alignment of the cylinder and tool is necessary.

Further and more limited objects of the invention will appear as the description proceeds and by reference to the accompanying drawings in which

Fig. 1 is a view in side elevation showing the preferred embodiment of my invention;

Fig. 2 is a view similar to Fig. 1 taken at right angles thereto with certain parts shown in section;

Fig. 3 is a vertical sectional view taken on the line 3—3 of Fig. 4;

Fig. 4 is a horizontal view, partly in section, taken on the line 4—4 of Fig. 1;

Fig. 5 is a top plan view of the tool which engages the valves;

Fig. 6 is a sectional view on the line 6—6 of Fig. 5; and

Fig. 7 is a fragmentary view in elevation showing the universal driving connection for the valve engaging member.

Referring now to the drawings, the apparatus consists essentially of a channel member 1 which is rigidly secured to the frame of a building by means of suitable bolts. Disposed at opposite sides of the channel members are a pair of vertically extending channel plates 2 and 3 which

are preferably welded in place. Disposed between the channel plates 2 and 3 are two pairs of spaced horizontally extending plates 4 and 5 welded to the channel plates and spaced apart by members 6. A horizontal plate 6 having a semi-circular recess 7 therein is welded to the channel plates and the upper plates 4 and 5 for receiving a cylindrical gas cylinder placed between the channel plates 2 and 3. Each of the channels 2 and 3 has a slot therein and mounted in said slots and between plates 4 and 5 are a pair of cams 8 and 9 secured in place by pins 10 and 11. These cams are eccentrically mounted and the peripheral portion thereof is toothed or serrated. These cams are operated by handle members 12 and 13 which extend outwardly through the slots in the channel plates 2 and 3. Secured adjacent the top of the channel member 1 is a channel shaped bar 14 and mounted thereon is a motor M and a speed reducing mechanism indicated generally by the reference character 15. Leading downwardly from the speed reducer is a shaft 16 which is connected with a sleeve 17 by means of a connector 18 which is connected with a standard frictional slip clutch 19. This clutch forms no part of the present invention and is known to the trade as a "Conway disk slip clutch."

This clutch includes a plurality of pressure plates which are urged toward each other by springs 20 so as to effect a driving connection. The clutch is engaged and disengaged in a manner well known to those skilled in the art and will begin to slip when excessive torque is encountered and will continue to slip until manually disengaged by means of a handle 21 which operates a lever 22 to move a pin 23 which operates a dog 24. Secured to the channel member is a pillow block 25 which has thereon a bearing 26. A hollow shaft 27 is journaled in this bearing and is operatively connected with the sleeve 17. Non-rotatably secured on the sleeve 27 is a coupling device including a pair of flanged couplings 28, which are adjustably mounted with respect to each other. This coupling device provides a universal driving connection for the valve engaging tool and permits vertical and angular movement thereof. Leading from the coupling device is a shaft 29 to the lower end of which is secured the tool engaging member 30 which has an angular recess therein adapted to engage different size valves or fittings.

When it is desired to insert a valve within the gas cylinder or container, the gas cylinder 31 is secured within the circular recess 7 in the plate 6 and the cams 8 and 9 moved to the position

shown in dotted lines in Fig. 4 so as to tightly grip the same. These cams serve to hold the cylinder against turning movement in either direction. The fitting of course is a threaded fitting and fits within a threaded opening in the cylinder. After the fitting has been started, the tool 30 is engaged with the fitting and the motor started by pressing the switch button 32 which serves to move the tool in a clockwise direction. When it is desired to remove the fitting, the switch button 33 is pushed which turns the tool in the opposite direction. Reference character 34 designates the stop switch which discontinues the operation of the motor. When the torque exerted on the tool exceeds a predetermined amount determined by the setting of the springs in the slip clutch, the clutch will slip and discontinue the rotation of the valve engaging member.

It will be seen that the tool engaging member is adjustable both angularly and as to height so as not to require any precise adjustment or setting of the tool. The universal connection also makes it unnecessary to have any precise alignment of the tool and the fitting to be engaged.

It will now be clear that I have provided a machine for applying and removing valve fittings in gas tanks which comprises a support, a holder carried by the support and means for holding the gas tank against turning movement in either direction together with a valve engaging member which is adapted for rotation in either direction and which has a slip clutch for automatically discontinuing the rotation of the valve engaging member when the force applied exceeds a predetermined amount. The unit includes a motor operated means for turning the valve engaging member in either direction, the driving connection for the valve engaging member including a universal joint and means permitting both vertical and angular movement of the driving connection.

The specific clutch mechanism and the specific universal driving connection are standard equipment which may be purchased on the open market and form no part of this invention.

It will now be clear that I have provided an apparatus for applying and removing valve fittings in gas cylinders which will accomplish the objects of the invention as hereinbefore stated. It is to be understood that the embodiment of the invention herein disclosed is to be considered merely as illustrative and not in a limiting sense as the invention is limited only in accordance with the scope of the appended claims.

Having thus described my invention, what I claim is:

1. In an apparatus for inserting and removing valves from cylindrical gas tanks, a vertical frame member for supporting mechanism for rotating the valves threaded into the gas tanks; a pair of parallel arm members extending from said frame, said arm members being spaced apart for receiving a gas tank therebetween; two pairs of spaced, horizontally extending plate members, one pair being attached to each of said arm members adjacent the ends thereof, respectively; and clamping means interposed between said plate members for engaging a gas tank between said arms, said means each comprising a cam, a pivot pin extending through the cam and having its ends journaled in said spaced plate members, and a handle extending outwardly from said cam for rotation of the cam.
2. In an apparatus for inserting and removing valves from cylindrical gas tanks, a vertical frame member for supporting mechanism for rotating the valves threaded into the gas tanks; a pair of parallel arm members extending from said frame, said arm members being spaced apart for receiving a gas tank therebetween and each arm having spaced, horizontally extending plate members adjacent the outer ends extending toward the opposite arm; and clamping means interposed between said plate members for engaging a gas tank between said arms, said means each comprising a cam, a pivot pin extending through the cam and having its ends supported in said spaced plate members, and a handle member extending from said cam outwardly through an opening in the adjacent arm member.
3. In an apparatus for inserting and removing valves from cylindrical gas tanks, a vertical frame member for supporting mechanism for rotating the valves threaded into the gas tanks; a pair of parallel arm members extending from said frame, said arm members being spaced apart for receiving a gas tank therebetween; two pairs of spaced, horizontally extending plate members, one pair being attached to each of said arm members adjacent the ends thereof, respectively; a horizontal plate extending intermediate said arm members, said plate having an arcuate recess in the outer edge thereof for receiving a gas tank placed between said arm members; and clamping means interposed between said plate members for engaging a gas tank between said arms, said means each comprising a cam, a pivot pin extending through the cam and having its ends journaled in said spaced plate members, and a handle extending outwardly from said cam for rotation of the cam.

WILLIAM H. LOVEMAN.
